US00D999909S

(12) **United States Design Patent** (10) **Patent No.:** **US D999,909 S**
(45) **Date of Patent:** **** Sep. 26, 2023**

(54) **CHEST TUBE INSERTION AID AND HANDLE ASSEMBLY**

(71) Applicant: **AOK Innovations, LLC**, Lexington, KY (US)

(72) Inventors: **Jon Kiev**, Lexington, KY (US); **Justen England**, Quincy, MA (US); **Chris Harris**, Cambridge, MA (US)

(73) Assignee: **AOK Innovations, LLC**, Lexington, KY (US)

(**) Term: **15 Years**

(21) Appl. No.: **29/884,222**

(22) Filed: **Feb. 8, 2023**

(57) **CLAIM**

The ornamental design for a chest tube insertion aid and handle assembly, as shown and described.

DESCRIPTION

FIG. 1 is a front perspective view of a chest tube insertion aid and handle assembly of the new design;

FIG. 2 is a front view of the invention illustrated in FIG. 1;

FIG. 3 is a rear view of the invention illustrated in FIG. 1;

FIG. 4 is a right elevational view of the invention illustrated in FIG. 1;

FIG. 5 is a left elevational view of the invention illustrated in FIG. 1;

FIG. 6 is a top view of the invention illustrated in FIG. 1;

FIG. 7 is a bottom view of the invention illustrated in FIG.

1; and,

FIG. 8 is a rear perspective view of the invention illustrated in FIG. 1.

The broken lines in the drawings depict portions of the chest tube insertion aid and handle assembly that form no part of the claimed design.

1 Claim, 5 Drawing Sheets
